UNITED STATES PATENT OFFICE

150,987

DESIGN FOR A COMBINED CLOCK AND SUPPORTING EASEL THEREFOR

Samuel J. Kaufman, New York, N. Y.

Application March 22, 1948, Serial No. 145,265

Term of patent 3½ years

(Cl. D42—7)

To all whom it may concern:

Be it known that I, Samuel J. Kaufman, a citizen of the United States, residing at New York city, in the county and State of New York, have invented a new, original, and ornamental Design for a Combined Clock and Supporting Easel Therefor, of which the following is a specification, reference being had to the accompanying drawing, forming a part thereof.

Fig. 1 is a front elevational view of a combined clock and supporting easel therefor, showing my new design.

Fig. 2 is a side view thereof.

The dominant features of the design reside in the portions shown in full lines,

I claim:

The ornamental design for a combined clock and supporting easel therefor, substantially as shown and described.

SAMUEL J. KAUFMAN.
